(57) **CLAIM**

The ornamental design for an apron with fold pocket, as shown and described.

DESCRIPTION

FIG. 1 is a front right side view illustrated on mannequin, the left front side being a mirror image of the right side. The phantom lines showing the bottom and top of the apron (i.e. the neck lines and the length lines) illustrate the environment only and form no part of the claimed design.

FIG. 2 is a front elevational view thereof; the apron being spread flat; and,

FIG. 3 is a rear elevational view of FIG. 2.

The dark thick broken lines in the FIGS. 1, 2, and 3 are understood to represent conventional stitching.

Any unshown portions of the apron are not part of the claimed design.
